UNITED STATES PATENT OFFICE.

WILLIAM A. BUTLER, OF INDIANAPOLIS, INDIANA, ASSIGNOR, BY MESNE ASSIGNMENTS, TO BUTLER ELLIPTICAL WRENCH MANUFACTURING COMPANY.

RATCHET-WRENCH.

1,359,325.

Specification of Letters Patent.

Patented Nov. 16, 1920.

Application filed August 9, 1918. Serial No. 249,123.

To all whom it may concern:

Be it known that I, WILLIAM A. BUTLER, citizen of the United States, residing at Indianapolis, in the county of Marion and 5 State of Indiana, have invented new and useful Improvements in Ratchet-Wrenches, of which the following is a specification.

This invention is an improved ratchet wrench for use in connection with a socket 10 for turning nuts on bolts and for other similar work, the object of the invention being to provide an improved wrench of this class by means of which a nut may be very rapidly turned until it becomes tight and 15 can then be turned forcibly by means of the handle and tightened to any desired extent or loosened in the same manner and then quickly removed.

With the above and other objects in view 20 the invention consists in the construction, combination and arrangement of devices hereinafter described and claimed.

In the accompanying drawings:

Figure 1 is a perspective view of a ratchet 25 wrench constructed and arranged in accordance with my invention and showing the same used in connection with the crank for rapidly turning a nut.

Fig. 2 is an elevation of the wrench with 30 the crank removed.

Fig. 3 is a sectional view of the same on the plane indicated by the line 3-3 of Fig. 2.

Fig. 4 is an elevation of the same with one 35 side removed and disclosing the ratchet wheel and the dog.

Fig. 5 is a detail inverted plan of the crank.

Fig. 6 is a diagrammatic plan showing the shoulder of the crank engaged in the 40 opening of the socket.

My improved wrench comprises a handle or lever 1 which is hollow and is formed with a substantially circular head 2 at one end and is also provided with a removable 45 side 3. The removable side is secured by means of screws 4. Two of these screws also serve to fixedly secure a dog or catch 5 in the hollow handle and which is arranged longitudinally thereof and near the head, as 50 shown. In the opposite side walls of the head are coincident elliptical bearing slots 6 extending lengthwise at an angle of about forty-five degrees to the longitudinal center of the handle, the longer sides of the slots 55 being parallel for a portion of their length. A ratchet wheel 7 is arranged for rotation

in the head and is provided with hubs 8 on opposite sides which are mounted revolubly and also slidably in the obliquely disposed elliptical slots 6. The ratchet wheel also has 60 an opening 9, of angular form in cross-section, extending therethrough and which is adapted to receive the shank or tubular portion of a socket member 15 which may be of any size and adapted to engage and receive 65 a nut of any size. A set of such sockets is provided with each wrench.

Owing to the provision of the elliptical slots 6 and the oblique arrangement of said slots with respect to the length of the handle 70 the ratchet wheel can be shifted by endwise movement of the handle instantly into or out of engagement with the dog or catch 5, and, hence, the ratchet wheel may be turned by step-by-step movement by means of the 75 handle and dog or may be, when disengaged from the dog, turned rapidly in and independently of the handle.

In order to thus rapidly turn the ratchet wheel and hence also the socket and the nut 80 or other work with which the socket is engaged, I provide a crank 10 which has a handle 11 on one side near the end and is provided at the opposite end with a projecting shoulder 12 which is squared and is 85 adapted to be detachably fitted into one end of the extension or hollow shank of the socket. To hold the crank thus engaged with the shank of the socket and prevent casual disengagement of the same, I provide 90 a frictional fastener in the specific form of a spring 13 which is here shown as a bowed or arcuate spring and which is secured on one side of the projecting shoulder 12 and is adapted to engage against one side of the 95 bore of the socket.

The handle with the ratchet wheel and dog are used for turning the socket forcibly and by step-by-step movement as when tightening or loosening a nut and the crank 100 is used for turning the nut rapidly as when starting or taking off the same and when the ratchet wheel by movement of the handle is shifted out of engagement with the dog. By reason of the dog 5 being placed longitudinally of the handle and having the teeth on both dog and wheel engage slightly before the end of the slot is reached by the ratchet wheel the strain due to a pull on the wrench is transmitted through the hub of the wheel 110 and the solid portion of the dog preventing the whole force from being thrown on the

teeth alone, thus avoiding a breaking of the teeth by the shearing stress produced.

Hence, my improved ratchet wrench enables the work of taking off or putting on a nut to be very rapidly performed.

Having thus described my invention, I claim:

1. A wrench comprising a handle, an elliptical slot formed thereon, a ratchet wheel having an angular opening therein journaled in said slot, a dog fixed to said handle having a single tooth thereon adapted to engage a ratchet tooth when the ratchet wheel is at one end of said slot, a socket having a hollow shank fitting into said angular

opening, and means adapted to be inserted into said shank for rapidly turning a nut.

2. A wrench comprising a handle, an elliptical slot formed thereon, a ratchet wheel having an angular opening therein journaled in said slot, a dog fixed to said handle having a single tooth thereon adapted to engage a ratchet tooth when the ratchet wheel is at one end of said slot, a socket having a hollow shank fitting into said angular opening, an angular member removably fitted into said hollow shank, and a crank handle fixed thereto.
